or for carrying a plurality of bottles suspended at their neck portions, with means to prevent accidental displacement of a bottle while suspended.

UNITED STATES PATENT OFFICE

2,512,060

BOTTLE CARRIER

Morton E. Harris, Chicago, Ill.

Application October 23, 1946, Serial No. 705,059

8 Claims. (Cl. 294—87.28)

1

This invention relates to improvements in bottle carriers and is more particularly concerned with devices of a kind useful for carrying bottled goods, such as, for example, carbonated beverages.

An object of the invention is to provide a bottle carrier which is adapted to receive a plurality of bottles suspended at their neck portions in such a way as to avoid their being bumped together while being carried.

Another object is to provide a bottle carrier of the kind from which bottles are suspended at their neck portions, with means to prevent accidental displacement of a bottle while suspended.

Another object is to provide an inexpensive bottle carrier of a kind that is durably constructed, light in weight and highly satisfactory in use; and one which is adapted to receive advertising material.

Other and further objects of the present invention will be apparent from the following description and claims and are illustrated in the accompanying drawing. Other embodiments of the invention embodying the same principle may be used and structural changes may be made as desired by those skilled in the art without departing from the present invention and a purview of the appended claims.

In the drawing:

Fig. 1 is a plan view of the bottle carrier showing the carrying handle broken away.

Fig. 2 is a central vertical sectional view taken on line 2—2 of Fig. 1, showing, in dotted lines, bottles suspended therefrom.

Fig. 3 is a sectional detail view taken on line 3—3 of Fig. 2.

Referring to the drawing, the bottle carrier, embodying the features of the present invention, is fashioned from sheet stock substantially circular in shape and includes a vertical surrounding wall portion 11 and a frusto-conical bottom wall 12. The bottom wall 12 is dished in the manner illustrated so as to dispose its central area 13 below the plane of its margin with the surrounding circular bottom wall portion inclined downwardly inwardly radially. The central area 13 preferably is formed with an upstanding boss 14 and the circular inclined area of said bottom wall has a plurality of circumferentially spaced key-hole shaped slots 15 surrounding the central area 13. Each of the key-hole shaped slots 15 is fashioned with its narrower slot portion 15a extending toward the central area 13 and its wider slot portions 15b disposed outwardly radially relative thereto.

2

Each slot 15 is adapted to receive the neck of a bottle 16, said neck initially being inserted from the bottom of the carrier upwardly through the wider slot portion and then moved inwardly radially into the narrower slot portion. Positioning of the bottle neck in the narrower slot portion 15a carries the margins of said narrower slot portion beneath the bead 17 of the bottle neck to thereby prevent withdrawal of the bottle from 10 the key-hole shaped slot.

It should be observed at this time that the key-hole slots 15 are so arranged and spaced relative to the other that when a plurality of bottles are suspended therethrough, the lower portions 15 of said bottles, which have the greatest circumference, are maintained in outwardly inclined positions substantially parallel to the plane of the inclined bottom wall 12 so as to prevent said bottles from contacting one another.

20 Inadvertant displacement of a bottle outwardly radially along its related slot 15 is prevented by means integrally attached to the boss 14. Such means is best shown in Fig. 2 and consists of a slightly dished piece of circular stock 25 18 riveted, as at 19, or otherwise secured at its center to the boss 14. The circular piece 18 is of a diameter to dispose its peripheral margin outwardly of the peripheral edge of each of the bottles 16 when they are suspended through the narrower slot portion 15a, and said circular member 30 is adapted to bear resiliently against the bottle tops to thereby prevent their rocking in their suspension mounting. A downwardly struck circular bead 21 is formed on the peripheral margin of the circular piece, which bead overlaps the 35 margins of the bottle tops underlying the same. Accordingly, each bottle is resiliently retained in place in the carrier and may be shifted outwardly radially into wider slot portions 15b upon overcoming the frictional resistance afforded by the 40 overlapping bead 21.

A carrying handle 22 may be fixedly attached as by means of rivets 23 to the upper edge of the circular wall 11 to afford means for handling the bottle carrier.

45 It should be quite evident at this time that the circular wall area 11 affords means to receive suitable advertising media which may be imprinted thereon or embossed therein and that, while a preferred form of construction has been 50 illustrated in detail in the accompanying drawings and fully described in the foregoing specification, the invention is capable of embodying a variety of modifications without departing from the spirit of the invention or the scope of the 55 appended claims.

I claim:

1. A bottle carrying device comprising a shallow container having its bottom wall radially inclined downwardly inwardly to locate its medial area below the plane of its margin, said bottom wall having circumferentially spaced key-hole shaped slots surrounding its medial area arranged so that the narrower portions of said slots are below the plane of the wider portions of said slots whereby a plurality of bottles may be inserted at their neck portions into the wider slot portions and be carried downwardly into the narrower slot portions so as to be suspended below the bottom wall, and means spaced above and overlying at least a portion of each of said key-hole shaped slots to retard movement of said bottles toward the wider slot portions and to hold said bottles in inclined positions.

2. A bottle carrying device comprising a shallow container having its bottom wall radially inclined downwardly inwardly to locate its medial area below the plane of its margin, said bottom wall having circumferentially spaced key-hole shaped slots surrounding its medial area arranged so that the narrower portions of said slots are below the plane of the wider portions of said slots whereby a plurality of bottles may be inserted at their neck portions into the wider slot portions and be carried downwardly into the narrower slot portions so as to be suspended below the bottom wall, and a resilient circular member spaced above the bottom wall and adapted to overlie at least a part of the narrower slot portion to prevent movement upwardly of bottles suspended through said slots.

3. A bottle carrying device comprising a shallow container having its bottom wall radially inclined downwardly inwardly to locate its medial area below the plane of its margin, said bottom wall having circumferentially spaced key-hole shaped slots surrounding its medial area arranged so that the narrower portions of said slots are below the plane of the wider portions of said slots whereby a plurality of bottles may be inserted at their neck portions into the wider slot portions and be carried downwardly into the narrower slot portions so as to be suspended below the bottom wall, and a resilient circular member spaced above the bottom wall and adapted to overlie at least a part of the narrower slot portion to prevent movement upwardly of bottles suspended through said slots, said bottom wall having an

axial boss extending upwardly therefrom and to which the circular member is secured.

4. A bottle carrying device comprising a dished member having a series of annularly-spaced bottle neck-receiving slots for supporting bottles by their necks, and resilient means spaced above said member and overlying at least a portion of each of said slots for holding said bottles against inadvertent outward radial displacement.

5. A bottle carrying device comprising a dished member having a series of annularly-spaced bottle neck-receiving slots for supporting bottles by their necks, and a resilient circular member concentric with said series of slots but spaced above said member and overlying at least a portion of each of said slots for holding said bottles against inadvertent outward radial displacement.

6. A bottle carrying device comprising a member having a series of annularly-spaced bottle neck-receiving slots arranged for supporting bottles by their necks, and resilient means spaced above said member and overlying at least a portion of each of said slots for holding said bottles against inadvertent outward radial displacement and in inclined suspended positions.

7. A bottle carrying device comprising a member having a plurality of spaced bottle neck-receiving slots arranged for supporting bottles by their necks, and resilient means spaced above said member and overlying at least a portion of each of said slots for holding said bottles against displacement and in inclined suspended positions.

8. A dished member having a centrally disposed boss in the concave surface thereof, and a series of annularly-spaced bottle neck-receiving slots for supporting bottles by their necks, and a resilient circular member supported on said boss and overlying at least a portion of each of said slots for holding said bottles against displacement and in inclined suspended positions.
